UNITED STATES PATENT OFFICE

ARTHUR LACHMAN, OF BERKELEY, CALIFORNIA, ASSIGNOR TO RICHFIELD OIL COMPANY OF CALIFORNIA, OF LOS ANGELES, CALIFORNIA, A CORPORATION OF DELAWARE

METHOD OF REFINING MINERAL OILS

Application filed June 22, 1927. Serial No. 200,589.

This invention relates to a method of purifying and refining mineral oils obtained by distilling or cracking, such as lubricating oils, kerosene, gasoline, shale oils, etc. The 5 method of refining mineral oils as described in this application is applicable to all mineral oils such as lubricating oils, kerosene, gasoline and shale oils, etc., and is particularly adaptable to oils obtained by a cracking process. For the purpose of simplifying the description, reference will be made to gasoline only.

Crude gasoline is usually obtained by distillation or by cracking of crude petroleum 15 and consists of a mixture of saturated and unsaturated hydro-carbons, together with asphaltic materials, sulphur compounds, nitrogen bases and other substances of an undefined nature. These latter substances are 20 readily oxidizable at ordinary temperatures and are responsible for the color changes which take place when refined gasoline is stored. These oxidizable substances are removed with difficulty when gasoline is refined by the methods now in common use.

In order to show the nature of my invention, it is desirable to describe the methods now in common use in oil refineries, and particularly that step of gasoline refining which 30 consists in de-odorizing and stabilizing the same. Crude gasoline obtained from the stills or cracking retorts, after condensation is treated with approximately 6 to 8 per cent by weight of sulphuric acid according to the 35 nature of the crude gasoline. The treatment usually consists in agitating the mixture of gasoline and sulphuric acid for an hour or more and then permitting it to settle, after which sulphuric acid sludge is withdrawn 40 and the gasoline is washed with a solution of alkali and finally with water. This treatment removes most of the impurities, but a subsequent treatment is frequently necessary in order to complete the de-odorization. For 45 this purpose a solution of sodium plumbite is commonly employed. The general objections to a treatment of this character are as follows:—

First, gasoline purified by this method is 50 frequently subject to discoloration upon stor-

age. Secondly, considerable quantities of sulphuric acid are required which are difficult to recover. Third, as much as ten per cent of the valuable hydrocarbons contained in the crude gasoline may be lost. Fourth, the treatment must frequently be followed with a de-odorizing process such as that described.

My invention consists in the discovery that the sulphuric acid normally used in refining crude gasoline may be replaced by zinc chloride and that gasoline treated with zinc chloride will be water white, stable as to color upon exposure to the air, and that this treatment will reduce crude gasoline losses to less than 2%.

The process briefly stated consists in treating gasoline or other volatile hydro-carbons by passing the same while in a vapor state through or in contact with a hot concentrated solution of zinc chloride. The gasoline so treated is usually pure enough for immediate use, although it sometimes may contain small amounts of hydrogen sulphide, which may be removed by washing with a weak alkaline 70 solution of sodium or calcium hydroxide, or of sodium carbonate.

The strength of the zinc chloride solution is from 70-85%. The temperature employed is around 150° C. normally fluctuating between 145 and 155. For the purpose of describing the process in more detail, reference will be made to the accompanying drawing, which is a diagrammatic view of one form of apparatus which may be employed.

Referring to this drawing, A indicates a cracking retort or the like from which the crude gasoline vapors discharge through the pipe-line 2. B indicates a tower of suitable height and diameter filled with resistant material, such as firebrick or the like indicated at 3 which forms numerous tortuous passages through the tower. Disposed above the tower or adjacent to the same is a tank containing a solution of zinc chloride having a concentration of 70-85%. This tank is connected with the top of the tower by means of a pipe 4 having a regulating valve 5. This pipe terminates over a spreader plate 6 and this plate evenly distributes the solution

when the valve 5 is opened over the brick-work or resistant material. The solution then flows downward through this material and may finally be discharged through the bottom by a pipe 7, after which it is treated for recovery. The tower is also provided with a steam or water inlet pipe 8 which intermittently or continuously supplies a predetermined amount of water to the tower. The vapor from the still or cracking retort A enters the lower end of the tower at a point 9. It passes up through the numerous tortuous passages in the brickwork and comes into intimate contact with the zinc chloride solution travelling or flowing over the same. Both solution and vapor are maintained at a temperature at from 145 to 155° C., and the vapor discharges at the upper end of the tower through a pipe 10 which is connected with a condenser 11 of suitable construction. The gasoline vapor entering at the temperature specified liberates and carries away a certain amount of water and the purpose of the steam or water inlet pipe 8 is that of continuously maintaining the solution at a certain water content so as to maintain the fluidity which is essential for good contact between the rising gas and the down-flowing solution. It is of great importance that the concentration of the zinc chloride solution is maintained at its predetermined limits by a continuous introduction of water or water vapor. Otherwise solid zinc chloride, and solid sludge impurities will plug the passages through which the gasoline vapors are being conducted.

It is further important that the solution of zinc chloride be saturated before it is introduced into the system with zinc hydroxide or zinc oxide. This may be accomplished either by agitating the solution of zinc chloride with these substances, or else by adding to it a small amount of sodium or calcium hydroxide. The optimum amount of zinc oxide or hydroxide is from 1 to 3 per cent of the weight of the zinc chloride solution.

Proportions required. The reaction tower B is kept full of zinc chloride, and zinc hydroxide solution, and a fresh supply of 15 lbs. solution, more or less, is admitted for each barrel (of 42 gallons) of gasoline continuously treated; a corresponding amount of spent solution is withdrawn at the same time.

The amount of water vapor required varies within rather wide limits, depending upon the concentration of the zinc chloride solution employed, the temperature at which operations are carried out and the nature and amount of inert gases which may accompany the gasoline vapor being treated. For each barrel of 42 gallons of gasoline there will be required approximately 15 pounds of concentrated zinc chloride solution, more or less, and from 50 to 100 pounds of water or water vapor. During this treatment the major

portion of the impurities are removed and carried out with the zinc chloride solution as a sludge, and the gasoline vapor when condensed is ready for use.

Having thus described my invention, what I claim and desire to secure by Letters Patent is:—

1. A method of refining mineral oils which consists in heating the oil to form a vapor, passing the heated vapor through or in contact with a maintained aqueous solution of zinc chloride and then condensing the vapor. 75

2. A method of refining mineral oils which consists in heating the oil to form a vapor at a temperature of approximately 150° C., 80 passing the heated vapor through or in contact with an aqueous solution of zinc chloride maintained at a similar temperature and then condensing the vapor.

3. A method of refining mineral oils which consists in heating the oil to form a vapor at a temperature of approximately 150° C., 85 passing the heated vapor through or in contact with an aqueous solution of zinc chloride maintained at a similar temperature, 90 and having a concentration of approximately 70-85% and then condensing the vapor.

4. A method of refining mineral oils which consists in heating the oil to form a vapor, 95 passing the heated vapor through or in contact with a maintained aqueous solution of zinc chloride containing zinc hydroxide, and then condensing the vapor.

5. A method of refining mineral oils which consists in heating the oil to form a vapor, 100 passing the heated vapor through or in contact with a maintained aqueous solution of zinc chloride containing from one to three per cent by weight of zinc hydroxide, and then condensing the vapor. 105

6. A method of refining mineral oils which consists in heating the oil to form a vapor, 110 passing the heated vapor through or in contact with an aqueous solution of zinc chloride containing from one to three per cent by weight of zinc hydroxide and zinc oxide, and then condensing the vapor.

7. A method of refining mineral oils which consists in heating the oil to form a vapor, 115 passing the heated vapor through or in contact with an aqueous solution of zinc chloride maintaining the solution in a fluid condition by addition of water and condensing the vapor after passing through the solution.

8. A method of refining mineral oils which consists in heating the oil to form a vapor, 120 passing the heated vapor through or in contact with an aqueous solution of zinc chloride containing zinc hydroxide, maintaining the solution in a fluid condition by addition of water and condensing the vapor after passing through the solution. 125

9. A method of refining mineral oils which consists in heating the oil to form a vapor, 130 passing the heated vapor through or in con-

tact with an aqueous solution of zinc chloride containing from one to three per cent by weight of zinc hydroxide and zinc oxide, maintaining the solution in a fluid condition by addition of water and condensing the vapor after passing through the solution.

10. A method of refining mineral oils which consists in heating the oil to form a vapor, passing the heated vapor through or in contact with an aqueous solution of zinc chloride, maintaining the concentration of the solution within predetermined limits by addition of water and condensing the vapor after passing through the solution.

15. A method of refining mineral oils which consists in heating the oil to form a vapor at a temperature of approximately 150° C., passing the heated vapor through or in contact with a maintained aqueous solution 20 of zinc chloride maintained at a similar temperature and having a concentration of approximately 70-85%, maintaining the concentration of the solution as specified by the continuous addition of water, and then condensing the vapor after passing through the 25 solution.

12. A method of removing from mineral oil, materials that tend to decolorize same on standing said method including the steps 30 of vaporizing the oil, contacting the vapor so obtained with a zinc compound including a maintained aqueous solution of zinc chloride and condensing the resulting vapor.

13. A method of removing matter that subsequently gives color to gasoline on standing, 35 said method including the steps of forming a vapor from the gasoline, contacting the vapor with a zinc compound including zinc chloride maintained in aqueous solution and condensing the vapor.
